UNITED STATES PATENT OFFICE.

THOMAS E. WOODLEY, OF NORWAY, MAINE, ASSIGNOR, BY DIRECT AND MESNE ASSIGNMENTS, TO CHARLES F. BROWN, TRUSTEE, OF READING, MASSACHUSETTS.

BOOT OR SHOE UPPER.

SPECIFICATION forming part of Letters Patent No. 423,709, dated March 18, 1890.

Application filed May 29, 1889. Serial No. 312,532. (No model.)

To all whom it may concern:

Be it known that I, THOMAS E. WOODLEY, of Norway, in the State of Maine, have invented certain new and useful Improvements 5 in Boot or Shoe Uppers, of which the following is a specification.

This invention consists in a boot or shoe upper having opposite short strips or welts attached to its outer surface near its edges at the ball portion, or between the shank and toe, said strips receiving the stitches that connect the sole and upper, and being stitched independently to the outer sole outside of the upper and re-enforcing or strengthening the 15 upper at the points which, in the use of the boot or shoe, are most liable to break away from said stitches.

It is well known that the greatest strain or wear is at the ball portion of a boot or shoe, 20 and hence it is unnecessary to have the welt extend entirely around the edge of the sole and upper. By my invention short opposite strips of welt are secured only at the ball portion of a boot or shoe, and as such material is quite expensive there is thus a great 25 saving in the cost of manufacture, and by cutting away or recessing the inner sole at the points where the welt-strips are located an even and uniform surface is obtained 30 throughout the inner sole of the shoe.

Of the accompanying drawings, forming a part of this specification, Figure 1 represents a sectional view of an upper having my improvement, the same being unattached to the 35 sole. Fig. 2 represents a transverse section of the upper secured to an outer and an inner sole. Fig. 3 represents a top view of the fore part of a completed boot. Fig. 4 represents a bottom view of part of an inner sole. 40 Fig. 5 is a view of a modification.

The same letters of reference indicate the same parts in all of the figures.

In the drawings, *a* represents the vamp portion of a boot or shoe upper, and *b b* represent the re-enforcing strips or sectional welts which constitute my improvement. Said 45 welts are attached by stitches *s* to the upper at opposite sides of the same, and are arranged to cover the inner edges of the upper 50 at the "ball" of the foot, or between the

shank and toe. The welts *b b* are composed of leather or other suitable material, and are stitched at *s* to the upper at their inner edges, said edges being about flush with the corresponding edges of the upper. The 55 outer edges of the welts project outwardly and lie on the upper surface of the outer sole. When the upper is attached to the outer sole *d*, the stitches *s'*, or other fastenings that unite said sole and upper, pass through 60 the strips *b b* as well as through the upper, said stitches or fastenings *s'* being between the stitches *s*, that secure the welts *b b* to the upper and the outer edges of said welts. The 65 welts are attached to the outer sole outside of the upper by stitches *s''*. It will be seen that the strips *b b*, receiving the fastenings *s'* and stitched to the outer sole outside of the upper, so strengthen and re-enforce the upper at the ball portion of the foot as to prevent liability 70 of said fastenings breaking the upper at this point, where liability of breakage is the greatest on account of the constant flexure of the foot in the act of walking. The strips give the upper the same strength as if its 75 thickness were considerably increased without impairing its flexibility. The independent stitches *s''*, uniting the welts to the outer sole outside of the upper, enable the welts to secure the upper to the outer sole even though 80 the stitches *s'* chafe and break. I am enabled by thus re-enforcing the upper to use a thinner inner sole than would otherwise be practicable, the strips *b* giving such support to the fastenings *s'* that an inner sole *t*, 85 composed of one or more layers of duck or other thin and flexible material, is found sufficient, the fastenings *s'* passing through said inner sole. Greater flexibility of the 90 boot or shoe provided with my improvement may therefore be obtained than without said improvement.

The strips *b b* may have perforations near their inner edges to receive a lasting-cord, as shown in Fig. 5, whereby the upper may be 95 secured to the last, said cord extending back and forth from one strip to the other across the bottom of the inner sole. Said cord may be allowed to remain in place in the completed boot or shoe, and in connection with 100

the strips b holds the upper in place to a certain extent independently of the fastenings s' , so that in case the upper should be detached from said fastenings the cord holding the strips b and the stitches s connecting said strips to the upper prevent displacement of the latter.

5 The inner sole t is preferably cut away or recessed at its sides to receive the sectional 10 welts, as shown at t' , Fig. 4, so that the thickness of the bottom will not be increased by said welts.

It will be seen that by means of my invention strips of welt of only minimum length 15 are necessary, and thus not only is there a great saving in the cost of material, but only a small space is occupied by the welt, and the inner sole being reduced or recessed at those points a uniform thickness is observed 20 throughout the length of the sole.

I claim

1. A boot or shoe having an upper provided with opposite short re-enforcing strips or sectional welts attached by stitches s to its 25 outer surface, and an outer sole attached to

the upper by fastenings s' , passing through and supported by said welts, and to the welts by independent stitches s^2 outside of the upper, as set forth.

2. The herein-described improved boot or shoe, consisting of the upper, the short strips or sectional welts secured to said upper at the ball portion thereof, the outer sole, the inner sole having opposite lower cut-away or recessed portions, beneath which portions of the said welts and upper are located, and the stitches securing said welts and upper and inner and outer soles, substantially as set forth, said inner and outer soles being in contact with each other, save at the ball portion 40 thereof, as stated.

In testimony whereof I have signed my name to this specification, in the presence of two subscribing witnesses, this 15th day of May, A. D. 1889.

THOMAS E. WOODLEY.
